CLAIM

The ornamental design for an E-cigarette case, as shown and described.

DESCRIPTION

FIG. 1 is a perspective view of an E-cigarette case showing my new design.

FIG. 2 is a front view thereof.

FIG. 3 is a rear view thereof.

FIG. 4 is a right end view thereof.

FIG. 5 is a left end view thereof.

FIG. 6 is a top view thereof.

FIG. 7 is a bottom view thereof.

FIG. 8 is another perspective view thereof.

FIG. 9 is a perspective view showing an open position in use thereof.

FIG. 10 is a front view thereof.

FIG. 11 is a rear view thereof.

FIG. 12 is a right end view thereof.

FIG. 13 is a left end view thereof.

FIG. 14 is a top view thereof.

FIG. 15 is a bottom view thereof; and,

FIG. 16 is another perspective view thereof.

The broken lines depicts unclaimed subject matter and form no part of the claimed design.
